CLAIM

The ornamental design for a package leaflet as shown and described.

DESCRIPTION

The patent or application filed contains at least one drawing executed in color. Copies of this patent or patent application publication with color drawings will be provided by the Office upon request and payment of the necessary fee.

The sole FIGURE is a front view of a package leaflet showing my new design.

The thickness of the package leaflet forms no part of the claimed design. The rear surface of the package leaflet is not claimed.

The broken line text throughout the drawing shows environment in which text exists but the content of the text forms no part of the claimed design.
